VERTICAL PIANO ACTION

Victor M. Montoya, Caracas, Venezuela

Application December 11, 1947; Serial No. 790,991

5. Claims. (Cl. 84—240)

1

This invention relates to an improved piano action for upright pianos through which the hammer is actuated by a key, and in particular an improved base for the impacting member wherein the base is provided with three interacting surfaces facilitating the coaction thereof with the impelling elements, an improved back check and wire post, an improved base control lever, and also the incorporation of an impelling member control lever.

The purpose of this invention is to provide an improved piano action which provides increased mechanical capacity thereby fulfilling minute playing requirements.

Various combinations of levers and mechanical instrumentalities have been provided for transmitting the action of a piano key to a hammer and particularly in the construction of an upright piano, it is necessary that the operating parts be incorporated therein in a definite relation in order that the piano will fulfill certain requirements and have good tonal quality. One of the essentials is that the key touch, which is the normal amount of force that the finger of a player applies to a key in order to obtain from the string the desired vibrating power and resonance, should be approximately two to three ounces which is standard for all pianos. The leverage of the key levers in modern upright pianos is such that a key lever will lift one end of the wippen operatively connected to its inner end, two-thirds of the distance that the key lever is depressed, as this ratio has been found by experience to give the most satisfactory results. The relation of the key lever to the several parts of the action also must be maintained with scientific exactness to enable such parts to move relative to one another with a minimum of friction and to obtain the most satisfactory results with the modern requirements of key touch, depth of touch, key lever leverage, and the amount of force with which the hammer hits the string at its striking point.

With these requirements in mind this invention contemplates a new upright piano action with increased mechanical capacity realized in the effective hammer impact by key impulse from any receding level stage comprising one-half course up, which is accomplished by a new disposition and the interaction of the elements, changes in the shape of the elements, and by the addition of new control elements.

The object of the invention is, therefore, to redesign and rearrange the elements of a piano action for upright pianos wherein greater efficiency and accuracy is obtained between the key and the hammer.

Another object of the invention is to provide, in a piano action, increased mechanical capacity that fulfills minute playing requirements.

A further object of the invention is to provide an improved piano action which is of a simple and economical construction.

2

With these and other objects and advantages in view, the invention consists in the new and novel combination, construction, and arrangement of parts as hereinafter more fully described, set forth in the claims appended hereto, and disclosed in the accompanying drawings, forming part hereof, wherein:

Figure 1 is a view showing a section through an upright piano with parts of the piano shown in section and the hammer and actuating parts thereof shown in elevation, illustrating the hammer in the position of rest.

Figure 2 is a similar view showing the position of the elements at the point of impact of the hammer with the wire.

Figure 3 is a similar view showing the position of the parts after the hammer rebound.

Figure 4 is also a similar view illustrating the positions of the parts at the time the key is released.

Referring now to the drawings wherein like reference characters indicate corresponding parts the improved hammer action of this invention includes a hammer butt or base 10, a jack 11, a wippen 12, a jack control lever 13, a hammer butt control lever 14, a back check 15, and other associated instrumentalities.

The hammer butt 10 is formed as illustrated in the drawings with a padded step 16 positioned to coact with the jack 11, a felt knob 17 positioned to engage the lever 14, and an end 18 adapted to be engaged by the pad 19 of the back check 15. The hammer butt is pivotally mounted on the support rail 20 by a pin 21 in the end of a flange 22, and a hammer 23 is supported thereon by a post 24. The post 24 rests on a pad 25 on a back rail 26 at the completion of the stroke.

The lower end of the jack 11 is pivotally mounted by a pin 27 in a socket 28 in the upper side of the wippen 12 and the wippen is carried by the lower edge of the support rail 20 through a flange 29 and a pin 30. The wippen is provided with an arcuate boss 31 having a pad 32 thereon by which it is engaged by a screw 33 on the end of a key 34 as illustrated in Figures 1 and 2. The end of the key rests upon a pad 35 on a base 36 and when the outer end of the key is pressed downward this end moves upward forcing the wippen upward, which through the jack 11 forces the hammer butt upward wherein the hammer is actuated to strike the wire 37, as shown in Figure 2.

The jack control lever 13 is pivotally mounted by a pin 38 on the lower end of the jack 11 and the outer end 39 thereof is resiliently held outward by a spring 40 on a screw 41 which is threaded into the lower end of the jack. The inner end of the lever 13 is provided with a knob 42 that is positioned to contact a pad 43 of a stop rail 44 on the rail 20 as the jack moves upward.

The hammer butt control lever 14 is also pivotally mounted on the jack 11 with the inner end

thereof held by a pin 45, and on the upper surface of the lever is a projection 46 that engages the knob 17 of the hammer butt, as shown in Figure 1. The lower surface of the lever 14 is provided with a clip 47 that holds the upper end of a spring 48, the lower end of which is pivotally mounted on the jack 11 by a pin 49, and the spring is resiliently held upward by a screw 50 which bears against an extension of the lower end. The tension of the spring is adjusted by the screw 50.

The outer end of the lever 14 is provided with a fork 51 in which a wire 52 is positioned, and the back check 15 which has a pad thereon is mounted on the upper end of the wire. The lower end of the wire is held in the end of the wippen and as the wippen is actuated the back check also moves upward so that it is positioned to engage the end 18 of the hammer butt after the hammer rebound as shown in Figure 3.

The hammer is resiliently urged backward by a spring 54 mounted in a rail 55 and held with the lower end of the spring bearing against the hammer butt 10 between ears 56.

With the parts arranged in this manner the impulse from the piano key 34 actuates the wippen 12 wherein the wippen forces the jack upward impacting the hammer butt and driving the hammer against the wire. The lever 13 governs the jack action and this is controlled by the combination of the stop 44 with the spring 43. In this movement the upper end of the jack slides along the inclined surface of the step 16, as shown in Figure 3, and in the rebound the knob 17 contacts the projection 46 of the lever 14 with the back check 15 stopping the hammer butt at half recoil. By this means increased mechanical capacity of the piano action is accomplished as in releasing the key lever, the parts descend accordingly except the lever 14, which reacts, retaining the hammer butt 10, permitting the jack 11 to gain attack position though key is at half up course.

The improved piano action of this invention, therefore, includes the five basic features, such as the new and improved shape of the impacting member base, wherein the base is provided with three interacting surfaces which facilitate the coaction therewith of the impelling member and the associated parts, the improved back check and wire post, the improved base control lever, and also the addition of a control lever for the impelling member. With these improvements the piano action fulfills minute playing requirements.

It will be understood that modifications may be made in the details of the improvements without departing from the spirit of the invention.

What is claimed is:

1. An upright piano action, comprising a hammer having a butt, a jack positioned to impact the butt of the hammer in the upward movement thereof, a wippen positioned to be engaged by a piano key and adapted to actuate the jack, a back check carried by the wippen positioned to contact the hammer butt, a support rail on which the hammer butt and wippen are pivotally mounted, a jack control lever pivotally mounted on the jack with one end extending toward the support rail, said rail having a stop thereon positioned to be engaged by the extending end of the said control lever, and means adjusting the position of said control lever.

2. An upright piano action, comprising a hammer having a butt, a jack positioned to impact the butt of the hammer with upward movement

thereof, a wippen positioned to be engaged by a piano key and adapted to actuate the jack, a back check carried by the wippen positioned to contact the hammer butt, a hammer butt control lever carried by the jack and pivotally attached thereto, said hammer butt control lever having a projection on the upper surface and a fork in the outer end in which the back check is positioned, a knob on the hammer butt positioned to contact the projection of the control lever, a spring on the jack urging the said control lever upward, and means adjusting the tension of said spring.

3. In an upright piano action, the combination, which comprises, a hammer having a base, a jack positioned to actuate the hammer through the base, a wippen positioned to be engaged by a piano key, a support rail carrying the hammer base and wippen and having a stop thereon, a jack control lever pivotally mounted on the jack having a knob on one end positioned to contact the stop on the rail, means adjusting the position of the control lever, a control lever pivotally mounted on the jack positioned to be contacted by the hammer base, means resiliently urging the control lever and the base upward, and a back check carried by the wippen and positioned to be contacted by the hammer base.

4. In a piano action including a supporting rail, a hammer, a base pivotally mounting the hammer on the rail, a jack, a wippen, and a key, the combination, which comprises, five basic features including a plurality of interacting surfaces on the base, one of said surfaces positioned to contact with the jack in the impelling action, a back check, a wire post supporting the back check from the wippen positioning the said back check to coact with one of the surfaces of the base, a base control lever pivotally mounted on the jack and positioned to coact with one of the surfaces of the base, and a control lever also pivotally mounted on the jack and positioned to coact with a stop on the rail to limit the operative travel of the jack.

5. A piano action for upright pianos comprising improvements in five basic features including an impacting member base having a plurality of interacting surfaces facilitating the coaction thereof with associated elements, a wippen, a back check carried by the wippen and positioned to be contacted by a surface of the base, a first control lever positioned to coact with another surface of the base for controlling the action of the said back check, an impelling member on which the control lever is pivotally mounted coacting with still another surface of the base, a second control lever for the impelling member pivotally mounted on said impelling member for limiting the operative movement thereof, and means for adjusting the second control lever.
